SAFETY AND LIKE PIN.

Application filed August 7, 1922. Serial No. 580,072.

To all whom it may concern:

Be it known that I, OSCAR E. RICHARDSON, a United States citizen, residing in Naugatuck, New Haven County, Connecticut, have invented the following described Improvements in Safety and like Pins.

The object of this invention is to reduce the possibility of accidental opening of safety pins, clasp pins, brooches, barrettes and the like, without substantial or any increase in the cost of their manufacture.

In the accompanying drawings the invention is illustrated in its preferred form as applied to an ordinary safety pin, Fig. 1 being a perspective and Fig. 2 a side elevation, both in large scale and the latter showing the pin in use.

It will be seen that the pin is formed as usual of a pair of relatively movable limbs united by a spring coil or hinge at one end, and that the pointed or penetrating limb 1, or pin proper, is received within a seat 2 in the head which is preferably a sheet-metal cap secured to the other limb or the body part of the pin, and from which it can be removed by pressing the pin toward the other limb or body part and then, or simultaneously shifting it sidewise. The invention is applied to such a safety pin by forming a notch in the cap adjacent to the bottom of the pin seat, so that the remaining part of the cap or seat forms a shoulder or shoulders, marked 3 in the drawing. This shoulder, or each of these shoulders, is substantially inflexible or rigid. It is spaced inward with reference to the pin. When the pin has been pushed through the material 4 in which it is used, the picked up part 5 of said material, especially if it is a full pickup, enters the space between the pin and the shoulder or shoulders 3 and thereby constitutes an obstruction to the exit of the pin from its seat, as will be apparent in the drawing, and such obstruction is found to form a most effective means of guarding against accidental opening.

The pin is of the outwardly seating type, the pin seat being disposed outward of the

seated pin which is pressed against the seat by its spring. The abutment means is blunt 50 and cannot pierce the cloth, but faces the right side of the picked-up material, i. e. the side from which the pin is being operated when the pin is in use, thus blocking movement of the pin inward from its seat, the 55 exit-blocking effect being produced by abutment means 3. It will be observed that the particular location or mounting of the shoulders is immaterial so long as they form an abutment facing the right side of the 60 picked-up material and adapted to sustain the picked-up material against pressure exerted on it by the pin in the opening direction. It is however desirable to accomplish this result without placing any part of the 65 pin structure in the path of pin movement from the pin seat, and it is a distinctive and advantageous, although not indispensable, feature of the invention, in its preferred forms and in association with other described structural arrangements characteristic of the invented pin, that the pin exit is not obstructed except by the picked-up 70 material, the cloth-sustaining means, or undercut portion with which the end of the cap 75 facing the picked-up material is provided, and which furnishes a space adjacent the seated pin to receive the material, being out of the line of pin movement from the pin seat. The pin is thus freely releasable on disengagement of the material from the undercut part of the cap. It will be observed 80 also that such material-sustaining member or members can be applied to any design or construction of outwardly closing clasp pin 85 or the like so long as the same comprises a seat from which the pin or penetrating limb is normally removable by inward movement transverse to its own length. It is preferred 90 that the abutment means shall be constituted of two proximate members or shoulders flanking the path through which the pin must be moved in order to escape from the seat, because this presents the most positive 95 means of supporting the picked up material against the pressure of the pin. In the case

of ordinary safety pins, the shoulders 3 are most conveniently formed when stamping the cap from the sheet stock from which it is made, and they are preferably given a slight 5 outward slope tending to retain the material in obstructing position. The word "undercut" used in certain of the claims has no reference to this outward slope and carries no implication as to any slope or angle. As 10 will be apparent, the pin may be readily opened when desired by manipulating it so as to disengage the material from the shoulders.

Claims—

- 15 1. A safety or like pin of the outwardly seating type comprising a head having a pin seat, a main limb, and a pointed limb, the latter being spring-pressed outward or away from the main limb and against said seat, and abutment means located opposite the part of the pointed limb adjacent the pin seat and co-operating with the pin seat to form a path or space adapted to permit the free and easy removal of the pointed limb 20 in the absence of pinned fabric between said abutment means and said limb part, but to block removal of the pointed limb when pinned fabric is between the abutment means and said limb part.
- 25 2. A safety or like pin according to claim 1 in which the head is a sheet metal cap having the abutment means, which provides fabric-contacting surface at each side of the pointed limb to contact with the side of the 30 picked-up fabric from which the pin is operated and thus support the pinned fabric athwart the path of the pointed limb from its seat, thereby preventing release of the pointed limb when pinned fabric is present 35 but permitting free and easy removal of the pointed limb in the absence of pinned fabric between said abutment means and said limb part.
- 40 3. A safety or like pin comprising a main limb having a pin seat and an outwardly inclined shoulder or shoulders adapted to retain and sustain the picked up material in position blocking the exit of the pin from its seat.
- 45 50 4. A safety or like pin of the outwardly seating type having a main limb providing a seat for the pointed limb disposed outward thereof and a pair of blunt cloth-obstructing abutment members flanking the pin and between which lies its exit path, and which provide means for sustaining the picked-up material athwart the exit path of the pin.
- 55 60 65 5. A safety or like pin comprising a main limb carrying a sheet metal cap having a pin seat and notched to provide a space between the seated pin and the cap facing the right side of the cloth and receiving the picked-up material thereby enabling the latter to occupy a position in which it blocks the pin exit.

6. A safety or like pin comprising a main limb carrying a cap providing a pin seat and having its end facing the right side of the picked up material provided with an undercut portion to permit entry of the picked-up 70 material between the seated pin and the said undercut portion of the cap and consequent obstruction by said material of the exit of the pointed limb from its seat.

7. A safety or like pin of the outwardly 75 seating type having a main limb carrying a sheet metal cap provided with a pin seat disposed outward of the pin and having blunt cloth-sustaining means located on the pin seat side of the cap and opposing the right 80 side of the cloth.

8. A safety or like pin having a main limb carrying a point-protecting cap forming a seat for the pointed limb and having a pair of shoulders, one at each side of the 85 pin, spaced inward with reference thereto, and leaving the pin exit unobstructed save for picked-up material sustained by said shoulders in position to block the pin exit.

9. A safety or like pin of the outwardly 90 closing type having a main limb carrying a point-protecting cap forming a seat for the pointed limb disposed outward thereof and having an undercut portion spaced inward with reference to the pin to permit entry of 95 the picked-up material between the pin and said undercut portion by which it is sustained in the exit path of the pin.

10. A safety or like pin of the outwardly seating type having a main limb providing 100 a seat for the pointed limb disposed outward thereof and a pair of blunt cloth-obstructing abutment members flanking the pin and between which lies its exit path, the abutment faces of said members being spaced inward 105 with reference to the pin and thus leaving cloth-receiving space for the picked-up material and providing means for sustaining it athwart the exit path of the pin.

11. A safety or like pin of the outwardly 110 seating type having a main limb, a sheet metal point-protecting cap carried thereby and having a seat for the pointed limb disposed outward thereof and having a pair of blunt cloth-obstructing members flanking the pin and between which lies its exit path, the abutment faces of said members being spaced inward with reference to the pin and thus leaving cloth-receiving space for the 115 picked-up material and providing means 120 for sustaining it athwart the exit path of the pin.

12. A safety or like pin comprising a main limb carrying a point-protecting cap providing a pin seat disposed outward of the 125 pin, and cloth-obstructing means facing the right side of the cloth, located out of the line of exit movement of the pin from its seat and spaced inward from the seated pin to leave room for the material to enter be- 130

tween the pin and said means and lie athwart the pin exit.

13. A safety or like pin comprising a pointed limb and a main limb carrying a sheet metal cap provided with a pin seat for the pointed limb located exterior thereto and having cloth-sustaining means out

of the line of exit movement of the pin from its seat and leaving the pin exit free when the picked-up material is removed from obstructing position. 10

In testimony whereof, I have signed this specification.

OSCAR E. RICHARDSON.
